By his Attorney,
Nelson M. Howard*

UNITED STATES PATENT OFFICE.

KARL ENGEL, OF ARLINGTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SOLE.

1,254,128.

Specification of Letters Patent. Patented Jan. 22, 1918.

Original application filed December 21, 1912, Serial No. 738,024. Divided and this application filed March 27, 1915. Serial No. 17,424.

To all whom it may concern:

Be it known that I, KARL ENGEL, a citizen of the United States, residing at Arlington, in the county of Middlesex, and State of Massachusetts, have invented certain Improvements in Shoe-Soles, of which the following description, in connection with the accompanying drawings, is a specification, like reference characters on the drawings indicating like parts in the several figures.

This invention relates to shoes and this application is a division of my co-pending application for patent on improvements in stock cutting processes, Serial No. 738,024, filed December 21, 1912, upon which was granted Patent No. 1,142,156 on June 8, 1915.

An object of the invention is to provide a shoe sole a portion of which may be made of relatively inferior material without detracting from either the durability or the appearance of the shoe. To this end, a feature of the invention consists in a pieced sole comprising a front portion and a rear portion having abutting edges substantially continuous across the sole and within the area of the heel seat and means for securing the two portions together to adapt the sole to be manipulated as one part. Since the rear portion of the sole, as thus formed, is not subject to wear, it may be made of relatively inferior and inexpensive material. In the construction shown the two portions of the sole have beveled overlapping ends, the rear end of the front portion being beveled on the side of the sole which is to be uppermost in the shoe. Since the two portions are so formed that their overlapping ends are substantially at the rear of the heel breast, and particularly in view of the fact that the front portion is beveled upon its upper side, the heel will overlap the front portion of the sole to a substantial extent and thus serve effectively when secured to both portions of the sole to prevent any tendency for the two portions to separate at the joint. Preferably also the two parts of the sole are secured together at their overlapping ends by fastenings located relatively near the rear edge of the front portion. Since any separation would occur first at the joint on the lower side of the sole, these fastenings are of material assist-

ance in maintaining the parts securely in proper relation.

In accordance with a further feature of the invention a sole is provided having two portions with substantially continuous abutting edges within the area of the heel seat and with fastenings extending in planes lengthwise of the sole to hold the two portions together as a unitary part. While fastenings of various kinds may be used consistently with the object of avoiding separation of the two portions of the sole prior to the attachment of the sole to the shoe and the object of providing a sole which shall form a durable part of the shoe, a particularly effective fastening means for this purpose comprises staples driven within the area of the heel seat in planes transverse to the line of junction between the two portions of the sole. The two legs of the staple thus provide a pair of fastening members spaced apart lengthwise of the sole and the crown of the staple serves as a binder which opposes effective resistance to separation of the parts due to bending of the sole. In a construction such as that shown, in which the two portions of the sole have beveled overlapping ends, the staples are preferably driven with both legs crossing the plane of the bevel, thus opposing double resistance to slip and leverage at the joint.

The above and other features of the invention will now be described with reference to the accompanying drawings which illustrate a preferred embodiment of the invention and will then be pointed out in the claims.

In the drawings:

Figure 1 is a perspective view of a sole in which the invention is embodied, and

Fig. 2 illustrates the use of the sole in a completed shoe.

The front portion 2 of the sole is cut preferably from sole leather, but may be of any material having the requisite wearing qualities. This portion is of such length as to extend rearwardly beyond the breast of the shoe heel and terminates in a straight edge 4. Pieces of this shape may be cut economically from a sheet of stock in the manner disclosed in my co-pending application hereinbefore referred to, of which this application is a division. At its rear end the

portion 2 of the sole is skived or beveled on its upper or flesh side for engagement with a corresponding bevel on a rear or heel seat portion 6 of the sole. This rear portion may 5 be made of relatively inferior material without detriment to the appearance or wearing qualities of the shoe and is shown as formed of scraps of leather cut to the proper shape and cemented together. The angle of bevel 10 at the overlapping ends of the two pieces is such as to provide a firm joint, and is preferably so formed with reference to the length of the piece 2 that the joint may not extend forwardly of the heel breast.

15 It is preferable to secure the two portions of the sole together by metallic fastenings, and in view of the fact that any opening at the joint due to bending of the sole in the use 20 of the shoe would occur first at the lower side of the sole it is preferable that the fastenings be located relatively near the rear edge 4 of the front portion. The fastenings shown comprise staples 8 driven in planes transverse to the line of junction of 25 the two portions and as close as possible to the edge 4, thus insuring a close joint at the lower side of the sole. Each staple thus provides virtually two fastenings spaced apart lengthwise of the sole, while the crown 30 serves as a binder which opposes effective resistance to separation of the parts of the sole by bending. Preferably the width of the staples used is so proportioned to the length of the bevel and the staples are so 35 driven that both legs extend across the plane of the bevel at the joint. This insures double resistance to slip and leverage between the two parts of the sole. The staples are most advantageously driven from the 40 lower side of the sole, as shown. It will be understood that as many fastenings may be used as found necessary or desirable, but in the use of a sole constructed and related to other portions of the shoe as shown and de- 45 scribed three staples have been found sufficient to insure a firm and durable joint.

By reference to Fig. 2 it will be seen that the heel covers the staples and overlaps substantially the front portion of the sole, the 50 joint at the lower side of the sole being located a substantial distance to the rear of the heel breast. The heel is thus secured to both portions of the sole and some of the heel nails may pass, as shown, through the 55 joint between the two portions to reinforce the joint. A shoe constructed in this manner is found to be fully as durable as one in which the sole comprises a single integral piece.

60 It should be understood that the joint between the two portions of the sole may take various forms and that the term "bevel" as used herein is not to be construed as limited to a surface presenting, as shown, a straight 65 slope in cross section.

Having described the invention, what I claim as new and desire to secure by Letters Patent of the United States is:—

1. A pieced sole comprising a front portion having its rear end beveled on the side 70 which is to be uppermost in the shoe, a heel seat portion of relatively inferior material having its front end beveled to overlap the beveled end of the front portion, the two portions of the sole being so formed that 75 their overlapping ends shall be positioned substantially at the rear of the breast of the heel of the shoe and in continuous engagement from one side of the sole to the other, and means securing the two portions of the 80 sole together to adapt the sole to be manipulated as one part.

2. A pieced sole comprising a front portion of sole leather formed of a length to extend rearwardly beyond the breast of the 85 heel of a shoe and having its rear end beveled on the flesh side, a heel seat portion of relatively inferior material having its front end beveled to overlap the beveled end of the front portion, the two portions of the sole 90 being beveled at such an angle that their overlapping ends shall lie substantially at the rear of the breast of the heel, and fastenings extending into the sole across the plane of the bevel at the joint between the 95 two portions of the sole to secure said portions together.

3. A pieced sole comprising a front portion having its rear end beveled on the side 100 which is to be uppermost in the shoe, a heel seat portion having its front end beveled to overlap the beveled end of the front portion, the two portions of the sole being so formed that their overlapping ends shall be positioned substantially at the rear of the 105 breast of the shoe heel, and means for securing said portions of the sole together at their overlapping ends comprising fastenings extending into the sole across the plane of the bevel at the joint and located relatively near 110 the rear edge of the front portion.

4. A pieced sole comprising a front portion and a rear portion relatively formed to cause the joint between the two portions to be located at the rear of the breast of the 115 shoe heel, the two portions of the sole having abutting edges in substantially continuous engagement across the sole, and fastenings connecting the two portions of the sole together to adapt the sole to be manipulated 120 as a unitary part prior to its attachment to the shoe, said fastenings comprising staples driven within the area of the heel seat in planes transverse to the line of junction of the two portions of the sole.

5. A pieced sole comprising a front portion and a rear portion relatively formed to cause the joint between the two portions to be located at the rear of the breast of the 130 shoe heel, the two portions of the sole hav- 1

ing beveled overlapping ends in substantially continuous engagement across the sole, and fastenings connecting the two portions of the sole together to adapt the sole to be manipulated as a unitary part prior to its attachment to the shoe, said fastenings comprising staples having both legs extending across the plane of the bevel at said joint, the legs of each staple being positioned also in spaced relation longitudinally of the sole.

6. A pieced sole comprising a front portion having its rear end beveled on the side which is to be uppermost in the shoe and formed of a length to extend rearwardly beyond the breast of the heel of the shoe, and a heel seat portion having its front end beveled to overlap the beveled end of the front portion, the two portions of the sole being secured together by staples each of which is driven in a plane transverse to the line of junction of the two portions and extends through the sole across the plane of the bevel at the joint and relatively near the rear edge of the front portion.

7. A pieced sole comprising a front portion and a rear portion relatively formed to cause the joint between the two portions to be located at the rear of the breast of the

shoe heel, the two portions of the sole having abutting edges in substantially continuous engagement from one side of the sole to the other, and fastenings extending in a row across the sole in planes lengthwise of the sole for connecting the two portions of the sole together, said fastenings being located within the area of the heel seat.

8. A pieced outer sole composed of a one-piece body having a fore portion, a shank portion, and an incomplete heel seat portion, a terminal forming a complementary heel seat portion attached to the body, the said body and terminal having continuous elongated abutting edges which meet within the area of the heel seat and form a joint extending continuously across the sole and arranged to be covered by the heel of the shoe of which the sole forms a part, and means for positively holding said abutting edges in contact with each other, to prevent edge-wise and sidewise movements of the terminal relatively to the body, the sole formed by said body and terminal being adapted to be manipulated and treated as one part.

In testimony whereof I have signed my name to this specification.

KARL ENGEL.
